 P. R. Mallory & Co., Inc., Indianapolis, Ind., a
 corporation of Delaware

Application August 28, 1946, Serial No. 693,546

5 Claims. (CL. 171—119)

1

This invention relates to transformers and, more particularly, to intermediate frequency transformers utilizing a core of pressed, powdered paramagnetic material.

Heretofore, conventional intermediate frequency transformers have ordinarily consisted of a can having a pair of coils mounted therein on an axially-extending insulating rod. With such a construction, it is necessary that the coils be spaced a considerable distance apart in order to obtain the rather loose coupling therebetween which is desired for intermediate frequency circuits. Furthermore, a pair of coils separated by a dielectric material such as air or an insulating rod have substantial exterior fields which necessitates spacing the shield can a considerable distance from the coils in order to minimize inductive losses. As a result of these factors, the conventional intermediate frequency transformer together with its trimmer condensers has occupied considerable space upon the chassis of the radio set which is undesirable in view of the modern tendency toward utilizing smaller sets together with circuit components of the minimum size therefor. As a further result of this construction, the adjustment of the coils to obtain the proper coupling is quite critical and difficult. These difficulties are accentuated by the fact that the top portion or peak of the resonance curve for the intermediate frequency transformer should be sufficiently broad to cover the entire audible range of frequencies, but, nevertheless, the resonance peak should be sufficiently narrow to provide a high degree of selectivity for the receiver. It will be appreciated, therefore, that critical adjustments are required to obtain proper resonance characteristics in the intermediate frequency portion of a superheterodyne circuit.

It is an object of this invention to provide a transformer of small size which will adequately fulfill the requirements of intermediate frequency circuits.

It is a further object of the invention to provide an intermediate frequency transformer which is readily adjustable to obtain the desired coupling between the coils and in which, after adjustment, the coupling is accurately maintained at its adjusted value.

It is a still further object of the invention to provide an intermediate frequency transformer having an efficient closed magnetic flux path for each coil with resultant elimination of stray fields.

It is a still further object of the invention to

2

provide a transformer of simple and economical construction which will operate reliably for long periods of time.

Other objects of the invention will be apparent from the following description and accompanying drawings taken in connection with the appended claims.

The invention accordingly comprises the features of construction, combination of elements, arrangement of parts, and methods of manufacture referred to above or which will be brought out and exemplified in the disclosure hereinafter set forth, including the illustrations in the drawings, the scope of the invention being indicated in the appended claims.

For a fuller understanding of the nature and objects of the invention as well as for specific fulfillment thereof, reference should be had to the following detailed description taken in connection with the accompanying drawings, in which:

Figure 1 is a vertical, sectional view, partially in elevation, of the novel intermediate frequency transformer;

Figures 2, 3 and 4 are, respectively, sectional views taken along the lines 2—2, 3—3 and 4—4 of Figure 1;

Figure 5 is a perspective view of the core;

Figure 6 is a schematic circuit diagram illustrating a feature of the invention; and

Figure 7 is a vertical, sectional view showing a modified core construction.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as generic in their application to similar parts as the art will permit.

Referring to the drawings in detail, and particularly to Figures 1 and 2, the transformer comprises a cylindrical shell 10 of pressed, powdered paramagnetic material. Mounted within the shell 10 are a pair of coil units 11, 12 which are separated by a spacer 13 of insulating material. Each coil unit includes a core 14 which comprises a generally cylindrical body 15. Figure 5, having longitudinal slots or grooves 16 formed therein which, preferably, extend along diametrically opposite surfaces of the core. The adjacent ends of the slots 16 are connected by end grooves or slots 17 which, preferably, extend

diametrically of the core structure 15. A pair of coils 18 and 19 are wound in the respective sets of slots formed in the cores so that the outer surfaces of each coil are flush with the periphery of the associated core as is clearly indicated in Figures 2 and 4. The coil units 11, 12 may be of identical construction and, in the example shown, the windings have the same number of turns.

Referring now to Figures 1 and 4, it will be seen that the shell 10 is enclosed by a support which consists of a base 20 of insulating material together with an insulating casing 21, this support being of generally rectangular cross section and holding the shell 10 and other parts to be described later. The insulating support, in turn, is enclosed by a metal shield, preferably of aluminum, which is formed by a base 22 and a casing 23. It will be observed that the base is flanged as at 24 to form an integral rigid container for holding the parts which make up the intermediate frequency transformer.

A pair of trimmer condensers 25, 26 of conventional design are mounted within the casing at the respective opposite ends of the shell 10 and the casing is suitably apertured to permit mounting of the trimmer condensers and access to the respective adjusting screws 27 thereon. The trimmer condenser plates, not shown, are connected to lugs 28, which, in turn, are connected in circuit with the coils by conductors 29 in such fashion that the trimmer condenser 25 is connected in parallel with the coil 18 and the trimmer condenser 26 is connected in parallel with the coil 19. Conductors 32 are also attached to the lugs 28, these conductors extending through suitable apertures in the casing and through the interspace between the shell 10 and the casing for connection to an external circuit.

It will be apparent from an inspection of Figure 1 that each of the cores 14 defines a closed magnetic path with the shell 10, such closed magnetic paths extending, respectively, around the coils or windings 18, 19. In this manner, the external field of the coils is substantially minimized or even eliminated so that the shield can may be placed directly in contact with the outer surface of the shell 10 or spaced therefrom a short distance as by the insulating members 20, 21. Moreover, the paramagnetic core structure results in a closed magnetic circuit of very low losses which insures efficient operation of the transformer.

In adjusting the transformer, coil units 11 and 12 are rotated relative to each other to thereby change the coupling between the windings 18 and 19. Although this adjustment is quite critical, as heretofore pointed out, the coupling may be accurately and conveniently accomplished by such rotation of the coil units. Thereupon, the coil units are fixed in position, as by bodies of wax or other sealing compound, as indicated at 33. As a result, the desired coupling is accurately maintained throughout the life of the transformer while, at the same time, a transformer of small dimensions which is very efficient in operation is obtained.

A modified form of core construction is shown in Figure 7. Since many parts of this modified core construction are similar to those already described, like parts will be indicated by corresponding reference characters. The core 10 of Figure 7 is directly in contact with an outer cylindrical metallic shield can 35. Mounted within the core are a pair of coil units 36, 37 and each of these

coil units comprises a cylindrical core 38 having a circumferential slot 39 formed therein. Each slot carries a winding 40, the outer surface of which is flush with the outer surface of the core.

5 The connections or terminal wires for the windings extend through slots 41 formed in the respective cores and these leads are connected to trimmer condensers, not shown, in the manner illustrated by Figure 6. In utilizing the modified core construction, the adjustment of the coupling between the coils is effected by longitudinal relative movement of the cores within the shell 10 rather than rotation thereof. When the desired coupling is obtained, the core units are 10 permanently fixed in place by bodies of wax or other suitable compound, as shown at 42. It will be apparent that the desired coupling between the windings can be readily attained and accurately maintained after the position of the 15 cores has been adjusted.

While the present invention, as to its objects and advantages, has been described herein as carried out in specific embodiments thereof, it is not desired to be limited thereby but it is intended to cover the invention broadly within the spirit and scope of the appended claims. Thus, for example, although I prefer to use iron for the material for the core units, the invention also 20 embraces the use of other paramagnetic materials. Further, although the shell 10 has been shown as a cylindrical shell, it is within the purview of the invention to utilize a square, oblong or other cross section for the shell.

What is claimed as new and desired to be secured by Letters Patent is:

1. In an iron core intermediate frequency transformer, a cylindrical shell of pressed, powdered iron, a pair of coil units mounted in said shell in direct contact therewith, each of said 25 units comprising a core of pressed powdered iron and a winding on said core, said units being rotatable relative to each other, within said shell to a predetermined angular relationship between said windings, and means for fixing said units in 30 said angular relationship within the shell.

2. In an intermediate frequency transformer; a pair of coil units each comprising an elongated core of pressed, powdered, paramagnetic material having a pair of longitudinally-extending 35 grooves, the adjacent ends of said grooves being connected by end grooved portions, and a winding supported in said grooves, the outer surface of said winding being flush with the outer surface of said core; and a supporting structure of pressed, 40 powdered, paramagnetic material enclosing said coil units along their longitudinal axes, said coil units being slidably displaceable within said structure.

3. In a transformer, a hollow structure of 45 pressed, powdered paramagnetic material, a pair of coil units mounted within said structure, the exterior of said coil units being contiguous with the interior surface of said structure, each of said coil units comprising a core of pressed, powdered 50 paramagnetic material and a winding on said core, and dielectric means separating said coil units, said coil units being rotatable, relative to each other, within said structure for varying the coupling between said windings.

70 4. A transformer structure comprising a shell of pressed, powdered paramagnetic material having a generally cylindrical inner surface, a pair of coil units mounted within said shell, each of said coil units comprising a generally cylindrical 75 inner core of pressed, powdered paramagnetic

material, said inner core having a pair of longitudinally-extending grooves, the adjacent ends of said grooves being connected by end-groove portions, and a winding supported in said grooves, the outer surface of said winding being flush with the surface of said inner core whereby said coil unit fits snugly within said shell, said coil units having axes lying in parallel planes, said axes being positionally adjustable, relative to each other, within said shell to a predetermined coupling position, and means for fixing said axes in said position.

5. A transformer structure, as set forth in claim 4, wherein the axes of said coil units, lying in parallel planes, are rotatably adjustable, relative to each other, for varying the angular relationship between said coil units whereby the coupling is varied.
